UNITED STATES PATENT OFFICE

106,571

DESIGN FOR A CIGARETTE LIGHTER

Raymond Loewy, New York, N. Y., assignor to Platinum Products Corp., New York, N. Y., a corporation of New Jersey

Application February 17, 1937, Serial No. 67,703

Term of patent 14 years

To all whom it may concern:

Be it known that I, Raymond Loewy, a citizen of France, residing in the county, city, and State of New York, have invented a new, original, and ornamental Design for Cigarette Lighters, of which the following is a specification, reference being made to the accompanying drawing, forming a part thereof;

I claim:

The ornamental design for a cigarette lighter as shown,

RAYMOND LOEWY,
